[57] CLAIM

The ornamental design for a passenger rail vehicle, as shown and described.

DESCRIPTION

FIG. 1 is an isometric view of a passenger rail vehicle showing my new design;

FIG. 2 is a top plan view thereof;

FIG. 3 is a right side elevational view, the left side being substantially a mirror image thereof except for the absence of two side doors and the engineer's window at the front end;

FIG. 4 is a bottom plan view thereof;

FIG. 5 is a rear elevational view thereof; and

FIG. 6 is a front elevational view thereof.

FIG. 1.

FIG. 2.

FIG. 3.

FIG. 4.

FIG. 5.

FIG. 6.
